CLAIM

The ornamental design for a barbecue grill shaped like bottle caps, as shown and described.

DESCRIPTION

FIG. 1 is a top, front perspective view of a barbecue grill shaped like bottle caps showing my new design;

FIG. 2 is a top plan view;

FIG. 3 is a front elevational view thereof, the rear elevational view being identical thereto;

FIG. 4 is a bottom plan view thereof; and,

FIG. 5 is a right side elevational view thereof, the left side elevational view being identical thereto.

The broken lines showing the support legs are for illustrative purposes only and form no part of the claimed design.
